POWER CONTROL

Milton J. Kittler, Detroit, Mich., assignor to
George M. Holley and Earl Holley

Application August 17, 1938, Serial No. 225,393

8 Claims. (Cl. 123—75)

The object of this invention is to enable an airplane engine to maintain its power either uniform or at a slight loss as the engine climbs.

If the pressure of the supercharger is maintained constant, there is inevitably a large increase of power as the plane ascends and the increase of power at 30,000 feet would be of the order of thirty per cent. It follows, therefore, that a constant supercharger pressure is not a complete solution. The maximum pressure at the air entrance at the inlet valves of the engine should constantly diminish as the altitude increases in order that the engine should develop its maximum power on the ground and should never exceed this maximum in the air at any altitude.

The figure shows diagrammatically the preferred form of my invention.

In the figure, 10 is a vacuum pump of well known design; 11 is a vacuum cylinder in which there reciprocates a piston 12 connected through a rod 13 with a piston 14 which reciprocates in the pressure cylinder 15, which communicates through the pipe 16 with the pressure side of the supercharger 17.

The details of the carburetor construction are omitted, and in the air entrance leading to the supercharger 17 is simply shown the throttle valve 18 located in an air passage. This throttle 18 is controlled by a lever 19 connected through a link 20 to a lever 21 rotatably mounted in the casting containing the cylinders 11 and 15. This lever 21 extends upwards and engages through a slotted opening 22 with a pin 23 projecting laterally from the rod 13. The oscillating lever 21 extends up to engage with the link 24 which has a one-way connection with a tube 25. This one-way connection is normally caused to act as a two-way connection by means of a spring 26, which seats against a washer 27 located on the link 24. A pin 28 on the right hand end of the tubular piece 25 is engaged by the manual lever 29 pivoted at 30 on the casting which carries the cylinders 11 and 15. A handle 31 is shown to control the movement of the throttle 18.

An adjustable spring 32 adjusted by a threaded spring support 33 is used to maintain the system in equilibrium.

Operation

When the engine is in operation, a constant pressure of say one pound absolute per square inch is maintained in the cylinder 11. Atmospheric pressure acts on the piston 12. Hence the tendency is as the atmospheric pressure

decreases for the pressure on the piston 12 to decrease, which permits the rod 13 to move to the right and thus permits the oscillating lever 21 to move in a clockwise direction to open the throttle 18 to maintain the power constant as altitude falls. When the levers 21 and 31 are moved in a counter-clockwise direction and the spring 26 is compressed, the throttle is closed. The net result is to overcome the effect of the spring 32 and thus reduce power. Meanwhile, the supercharger pressure is acting on the piston 14 which, it will be noticed, is slightly larger than the vacuum piston 12. The tendency of an increase in supercharger pressure is to also move the oscillating lever 21 in a counter-clockwise direction, that is to say, to close the throttle.

At every position of the hand lever 31 equilibrium will be reached when the following forces are in balance—the supercharger pressure acting on the piston 14, the atmospheric pressure acting on the difference in area between the pistons 12 and 14 and the compression of the spring 26 acting against the spring 32. There will, therefore, be a tendency for the throttle to open as the plane rises in altitude, because as the engine rises, there will be a tendency for the atmospheric pressure acting on the piston 12 to fall and there will also be a tendency for the supercharger acting on the piston 14 to fall. The decrease of both of these causes a clockwise movement of the oscillating lever 21, and therefore an opening movement of the throttle 18.

As the piston 14 is slightly larger than the piston 12, an increase in atmospheric pressure (decrease in altitude) has a tendency to cause the throttle to open. This opposes the tendency of a constant supercharger pressure to increase the power as altitude increases. If the throttle 40 is in the position shown, we will assume that it permits the engine to develop its rated power on the ground at sea level. Then, as the plane rises, the throttle will open automatically under the influence of the spring 32 to maintain the 45 supercharger pressure in 15 at the figure determined by the adjustable spring support 33. As the piston 14 is larger than the piston 12 by a slight amount, the corresponding decrease in atmospheric pressure acts as a force acting on 50 the left and therefore, weakens the spring 32, or it rather opposes the spring 32 so that there is a tendency for the decreased atmospheric pressure to close the throttle which is the desired result. By this means, the engine will 55

never be called upon to develop more than the maximum power which it developed when taking off at sea level.

The two reasons why a constant supercharger pressure gives an increasing horsepower with decreasing air pressure are:

1. A lower back pressure raises the horsepower for a given inlet pressure.

2. By reason of the low atmospheric pressure the exhaust gases in the cylinder when the exhaust valve closes and the inlet valve opens are at a low figure, say seven pounds per square inch. Assuming that the supercharger pressure is at say 16 pounds per square inch, then we get air and mixture flowing into the cylinder under a pressure differential of nine pounds per square inch. Thus, the charge is much greater than it is at sea level and this is the major cause of the increase of power if the supercharger power is maintained constant. This increase is of the order of one per cent per 1000 feet.

Obviously, instead of locating the vacuum cylinder 11 and the pressure cylinder 15 on the same axis, the pressure cylinder 15 may be made of the same diameter as the vacuum cylinder 11 and located so as to have a greater mechanical advantage, which, of course, is the full equivalent of making the pressure cylinder 15 larger and locating it on the same diameter as the chamber of the vacuum cylinder.

An arcuate projection 34 engages in an arcuate guide 35 to hold the manual control 31 in any given position. In long flights the throttle control is positively locked in some given position, but the locking means are not shown in this drawing.

Attention is drawn to the fact that the throttle 18 can be positively opened and positively closed by the throttle control lever 31. In other words, the control of the throttle can be taken completely away from the automatic control. This is because the compression spring 26 is adapted to collapse on itself when it acts as a solid connection between the lever 21 and the link 25.

What I claim is:

1. In a throttle controlled supercharged engine, a throttle lever, a manually operated link having a positive one-way connection adapted to positively open the throttle, a loose connection and a spring associated therewith permitting the throttle to be yieldingly closed, a second spring adapted to open the throttle, means responsive to the pressure of the supercharger also connected to said throttle lever and adapted to open the throttle until the pressure of the supercharger above the atmospheric pressure equals the pressure determined by the second spring.

2. A device as set forth in claim 1 in which

adjustable means are provided for adjusting the effect of said second spring.

3. A device as set forth in claim 1 in which means are provided responsive to a decrease in atmospheric pressure to permit a lower supercharger pressure to be maintained at low atmospheric pressure.

4. In a throttle controlled supercharged engine, a throttle lever, a source of vacuum, a vacuum cylinder, a piston therein, spring means connected with said lever so as to oppose the action of the vacuum, means for admitting atmospheric pressure to the other side of the piston, a second cylinder, a piston therein subjected on one side to the pressure in the supercharger, means for admitting atmospheric pressure to the other side of the piston, means for connecting both pistons to the throttle lever so that the vacuum means and the supercharger pressure means act in the same direction, manual means for moving the throttle lever to an open position, a yielding connection between said manual control means and said throttle lever, the piston responsive to the action of the supercharger pressure being adapted to close the throttle when the supercharger pressure exceeds a figure determined by the spring whereby the pressure in the supercharger is automatically maintained at a figure determined by the spring.

5. A device as set forth in claim 4 in which the diameter of the piston responsive to supercharger pressure is slightly greater than that of the piston responsive to the vacuum and both pistons are located on the same centerline.

6. A device as set forth in claim 4 in which the leverage exerted by the piston responsive to the supercharger pressure is slightly greater than the corresponding leverage exerted by the vacuum responsive piston.

7. A device as set forth in claim 4 in which the yielding connection between the manual control means and the throttle lever comprises a second spring adapted to oppose the first mentioned spring when the manual control is moved to its closed position so that the pressure in the supercharger is maintained at a lower figure when the manual control is moved away from the wide open towards the closed throttle position.

8. A device as set forth in claim 4 in which the yielding connection between the manual control means and the throttle lever comprises a compression spring adapted to be compressed when the manual control means is moved towards its closed throttle position, and this compressed spring then acts in opposition to the first mentioned spring so as to lower the pressure which is automatically maintained in the supercharger when the throttle control lever is moved away from its wide open position.
